CLAIM

The ornamental design for a multi-badge dosimetry vest, as shown and described.

DESCRIPTION

FIG. 1 is an outside elevational view of a multi-badge dosimetry vest spread flat, showing my new design;

FIG. 2 is an inside elevational view thereof;

FIG. 3 is a front perspective view thereof, the garment being shown in the position of use;

FIG. 4 is a rear perspective view of FIG. 3.

FIG. 1

FIG. 2

FIG. 4

FIG. 3
